DESIGN FOR A CABINET FOR SPACE
HEATERS OR THE LIKE

Carl S. Greer, Jr., Albion, Mich., assignor to Gamble Stores Incorporated, Minneapolis, Minn., a corporation of Minnesota

Application October 9, 1947, Serial No. 141,837

Term of patent 14 years

(Cl. D81—19)

To all whom it may concern:

Be it known that I, Carl S. Greer, Jr., a citizen of the United States, residing at Albion, in the county of Calhoun and State of Michigan, have invented a new, original, and ornamental Design for Cabinet for Space Heaters or the like, of which the following is a specification, reference being had to the accompanying drawing, forming a part thereof in which:

Fig. 1 is a perspective view of a cabinet for space heaters or the like embodying my new design; and

Fig. 2 is a top plan view of the design of the cabinet shown in Fig. 1.

The side of the cabinet not shown is substantially the same as the side shown.

I claim:

The ornamental design for a cabinet for space heaters or the like, substantially as shown and described.

CARL S. GREER, JR.
